UNITED STATES PATENT OFFICE

2,660,321

APPARATUS FOR REMOVING SLABS FROM
HEATING FURNACESHarvey Demmon and Mansel E. Houk, Pittsburgh,
Pa., assignors to United States Steel Corpora-
tion, a corporation of New Jersey

Application December 26, 1951, Serial No. 263,254

3 Claims. (Cl. 214—18)

1

This invention relates to improved apparatus for removing metal slabs from continuous heating furnaces.

Furnaces of this type have elongated alloy steel skids which extend from their entry to their exit ends and in normal operation of the furnace support a row of slabs along their entire length in abutting relation. The cold slabs are charged to the entry end by a pusher which advances the entire row of slabs along the skids and discharges the last slab from the exit end to a hot mill run-out table. Thus the furnace is kept filled with slabs in various heating stages. When it is necessary to shut down such a furnace, the usual practice is to charge dummy or defective slabs in like manner until all the prime slabs are pushed through. Then the furnace is cooled with the dummy slabs remaining on the skids. If it is necessary to remove them to make repairs to the furnace, they are dragged out with a cable or chain. This practice is both time consuming and requires having available a large number of dummy slabs, which take considerable space.

An object of the present invention is to provide an improved slab removing apparatus which itself is readily removable from a heating furnace and occupies a minimum of space in storage.

A more specific object is to provide an improved slab removing apparatus which includes a plurality of frame sections adapted to be coupled together end to end and to extend between the pusher and the rearmost slab in a furnace for advancing a row of slabs, and a coupler adapted to attach said sections to the pusher for removing them from the exit end of the furnace.

In accomplishing these and other objects of the invention, we have provided improved details of structure, a single form of which is shown in the accompanying drawings, in which:

Figure 1 is a top plan view of a slab heating furnace from which slabs are being removed by use of the apparatus of the present invention, the furnace roof being broken away;

Figure 2 is a vertical sectional view taken on line II—II of Figure 1;

Figures 3 and 4 are top plan and side elevational views respectively on a larger scale of one of the frame sections of the apparatus;

Figures 5 and 6 are side and end elevational views respectively on a still larger scale of one of the connectors for coupling the frame sections;

Figure 7 is a fragmentary side elevational view on a larger scale than Figures 3 and 4 showing a detail of the preferred construction of frame section; and

2

Figures 8 and 9 are top plan and side elevational views of the coupler used to connect the frame sections to the pusher.

Figures 1 and 2 show somewhat schematically a slab heating furnace which comprises refractory side walls 10 and elongated horizontal alloy steel skids 12. A charging table 13 and a pusher 14 are situated at the entry end (the left as viewed in Figure 1) and a hot mill run-out table 16 at the exit end. In normal operation cold slabs S are introduced to the charging table 13 by handling mechanism, not shown. The pusher 14 then pushes such slabs one by one into the furnace where they are supported on skids 12. As the pusher moves each cold slab into the furnace, it advances the entire row of slabs and thus pushes the last slab, which has become fully heated, through the furnace exit to the run-out table 16. Inasmuch as such furnaces and pushers are well known, no more detailed description is deemed necessary.

The present invention provides a plurality of frame sections 17 which are adapted to be coupled together end to end and to extend between the pusher 14 and the rearmost slab S for advancing the row of slabs without the necessity for charging additional slabs when it is desired to empty the furnace. A sufficient number of such sections are used to extend the full length of the skids and thus to enable the rearmost slab to be expelled from the furnace. After each section 17 is pushed into the furnace, the pusher is retracted so that the next section can be coupled to the row of sections already in the furnace.

Figures 3, 4 and 7 show details of a preferred construction of frame section. Each frame section includes structural members, such as pipes, welded together to form longitudinal members 18 and cross braces 19. Angle irons 20, which face upwardly and inwardly, are welded to the ends of said longitudinal members and braces. Each angle iron carries a pair of lifting lugs 21 adapted to be engaged by handling mechanism, as indicated in Figure 4. The angle irons are canted slightly with respect to the longitudinal members, so that they have only line contact with the skids when the section is within a furnace. This small contact cuts down heat transfer to the sections and thus prolongs their useful life. The cant is obtained by inserting small spacers 22 between the angle irons and the longitudinal members, as illustrated in Figure 7.

Connectors 23 are used for coupling the frame sections together. As shown in Figures 5 and 6, 55 each of said connectors has a notch 24 in its un-

derside adapted to receive the upright flanges of two angle irons 20 of a pair of abutting frame sections 17. The top of each connector preferably carries a lifting lug 25. Commonly two such connectors are used for coupling each abutting pair of frame sections.

Figures 8 and 9 show details of a preferred coupler 26 for attaching the frame sections 17 to the pusher 14 for removing them from the furnace. This coupler includes a pair of spaced apart bars 27 joined by a cross piece 28. Said bars have notched connectors 29 at their forward ends adapted to engage over the angle iron 20 of the rearmost frame section 17 and hook portions 30 at their rear ends adapted to engage the pusher 14. Preferably the upper face of each bar 27 carries a lifting lug 31.

In operation, when it is desired to empty the furnace, the pusher 14 is used to push a frame section 17 into the entry end of the furnace against the row of slabs S in the same way that cold slabs normally are introduced. When the first section is fully advanced, the pusher is retracted and a second section 17 is coupled to the first such section by a pair of connectors 23. The two sections thus coupled then are advanced in the same fashion as the first. This procedure is continued until all the slabs are expelled from the exit end of the furnace. Next the coupler 26 is used to attach the rearmost section 17 to the pusher. The pusher is operated to withdraw the whole assemblage of frame sections toward the exit end a distance of one section length, after which the rearmost section is uncoupled by removal of connectors 23 and removed. This procedure is continued until all the frame sections are removed.

From the foregoing description it is seen that the present invention furnishes an apparatus of simple construction for expeditiously removing slabs from heating furnaces. The apparatus itself subsequently is readily removed from the furnace. The small contact between the frame sections and the furnace skids effectively protects the sections against overheating, and the sections require but little storage space.

While we have shown and described only a single embodiment of the invention, it is apparent that modifications may arise. Therefore, we do not wish to be limited to the disclosure set forth but only by the scope of the appended claims.

We claim:

1. A frame section for pushing slabs from a heating furnace comprising longitudinal members and cross braces welded together, upwardly and inwardly facing angle irons welded to the ends of said longitudinal members, and spacers interposed between said angle irons and said longitudinal members canting said angle irons so that they have only line contact with a supporting surface.

2. An apparatus for removing slabs from a heating furnace comprising a plurality of frame sections adapted to be pushed into a furnace in end to end abutting relation against the rearmost slab, each of said frame sections being formed of longitudinal members and cross braces welded together and angle iron end pieces welded to said longitudinal members and facing upwardly and inwardly, connectors having downwardly facing notches receiving the upright flanges of the angle iron end pieces of each pair of abutting frame sections and thus removably coupling these sections together, and a coupling adapted to connect the rearmost frame section with a furnace pusher for removing the sections one by one from the exit end of the furnace.

3. An apparatus as defined in claim 2 in which spacers are interposed between said angle iron end pieces and said longitudinal members to cant the end pieces and thus furnish only line contacts between the frame sections and the furnace.

HARVEY DEMMON.
MANSEL E. HOUK.
